UNITED STATES PATENT OFFICE.

JOHN J. KILBRIDE, OF NEW YORK, N. Y.

MULTIPLE-VALVE GRINDER.

Application filed July 10, 1925. Serial No. 42,803.

This invention relates to valve grinders, and has particular reference to a valve grinding device for automobile engines.

The principal object of the present invention is to provide an improved valve grinder by means of which the entire set of valves of a motor may be simultaneously ground in one operation, thereby effecting economy both in time and labor.

10 More specifically the invention comprehends a multiple valve grinder which consists of an element for coupling the valves of a complete set to each other, whereby the valves are simultaneously ground, and in which the coupling means preferably consists of a slotted element or bar which carries a plurality of relatively adjustable valve-engaging elements, whereby the device is capable of use in connection with valve sets which are variously spaced.

It is a further object of the invention to make the valve-engaging elements adjustable to bring the connecting bar closer to or farther from the valve heads.

25 The invention furthermore comprehends a multiple valve grinder which is comparatively simple in its construction and mode of operation, inexpensive to manufacture, and which is highly efficient in its purpose.

30 With the above and other objects in view, reference is had to the following specification and drawings in which there is exhibited certain examples or embodiments of the invention which are in no way intended as limitations upon the scope of the appended claims as it is to be clearly understood that variations and modifications which properly fall within the scope of said claims may be resorted to when found expedient.

In the drawings—

Figure 1 is a longitudinal sectional view illustrating the valve grinder in use;

Fig. 2 is a fragmentary plan view thereof;

Fig. 3 is a plan view illustrating a pair of valve-grinding devices coupled in ganged relation for use in connection with valve sets including a large number of valves;

Fig. 4 is a detail transverse sectional view on an enlarged scale;

Fig. 5 is a side view of a slightly modified adaptation of the invention.

Referring to the drawings by characters of reference, the valve grinder comprises a valve coupling member 10, which in the pre-

ferred embodiment or example of the invention, is in the nature of an elongated bar having a longitudinal central slot 11, the lower portion 12 of which is of greater width than the upper portion, to afford a seat for a plurality of nuts 13, through which the stems 14 are threaded, the lower unthreaded extremities 15 of which project below and are engageable within the usual diametrically spaced openings A in the valve head B, whereby they constitute valve-engaging means. The upper portions of the threaded stems 14 project above the bar 10 and extend through washers 16, after which thumb nuts 17 are applied for the purpose of holding or clamping the valve-engaging extremities 15 in relatively spaced relation within the slotted bar 10. It will be further noted that by threading the stems 14 through the nuts 13, vertical adjustment of the stems 14 with respect to the bar 10 may be effected for the purpose of adjustably projecting the stem terminals 15 from the under side of the bar 10, to dispose said bar closer to or farther from the valve heads. At its opposite ends the bar 10 is provided with upwardly projecting manipulating handles 18 for the purpose of effecting rotary movement of the valve heads to accomplish the grinding operation. The handles 18 are preferably detachably associated with the bar 10 by engaging the threaded stems 19 in threaded apertures 20 in the bar.

In order to render the device capable of a wide range of use, each bar is provided, adjacent its opposite ends, with coupling means whereby a plurality of bars 10 may be connected to each other, as illustrated in Fig. 3, for the purpose of bringing into use a greater number of valve engaging elements where the valve set consists of eight, twelve, or more valves.

In the present instance the coupling means is illustrated as interengaging dovetails 21 and 22 at the opposite ends of the bar, which are approximately half the thickness of the bar with an underlying shelf 23. In order to prevent disengagement of the dovetails, clip elements 24 fasten the dovetails 100 in interengaging relation by anchoring screws 25.

In some instances the valve heads C, as illustrated in Fig. 5, are formed with an elongated recess D in lieu of the diametrical- 110 ly disposed openings A as in Fig. 4, and in order to compensate for this variation plates

26 are provided having ribs 27 on their under side which are designed to engage within the recesses D, the said plates being provided with an opening 28 to receive the valve-engaging terminal 15 of the device.

In use and operation, the stems 14 are adjusted relatively to each other to coincide with the spacing of the valves B by loosening the thumb nuts 17 and registering the 10 terminals 15 with the openings A of the valves, after which the thumb nuts are tightened to maintain the adjustment. With the terminals 15 engaging within the openings of the valves of the set, the handles 18 15 are manipulated to effect a rotary movement for grinding the valves in unison.

Where the set includes a greater number than four valves, an additional bar or bars 10 are added by coupling the stems to each 20 other as set forth and illustrated in Fig. 3.

From the foregoing it will thus be seen that a multiple valve grinder has been designed, which is extremely simple both in its construction and mode of operation, and 25 which is comparatively inexpensive to manufacture.

What is claimed is:

1. A multiple valve grinder, comprising a bar having a plurality of relatively adjustable valve-engaging elements eccentrically engaging and coupling the valves, said elements connected to the bar to necessarily partake of circular movements upon attempted reciprocations of the bar, and 35 means on the bar for facilitating reciprocatory movement of the bar to simultaneously grind the valves.

2. A multiple valve grinder, comprising a longitudinally slotted bar, a plurality of 40 valve-engaging elements mounted in the slotted portion for relative adjustments and fixed to said bar for rotary movements upon attempted reciprocations of the bar, and means thereon for facilitating movement of 45 the bar to simultaneously grind the valves.

3. A multiple valve grinder, comprising a longitudinally slotted bar, a plurality of valve-engaging elements adapted to eccentrically engage the valves and mounted in the slotted portion for relative adjustment 50 and fixed thereto in such a manner as to necessarily partake of circular movements upon attempted reciprocations of the bar, means for retaining said elements in relatively adjusted relation, and manipulating 55 means on the bar for facilitating rotary movement of the bar to simultaneously grind the valves.

4. A multiple valve grinder, comprising a member and means thereon for facilitating 60 movement of the member to simultaneously grind the valves, a plurality of valve-engaging elements adapted to eccentrically engage the valves mounted on the member for relative adjustment and fixed thereto in such a 65 manner as to necessarily partake of circular movements upon attempted reciprocations of the member, said member having means at its opposite ends adapted for interengagement with similar means on another member, whereby to increase the length of the 70 valve grinder to accommodate valve sets including a greater number of valves.

5. A multiple valve grinder, comprising a longitudinally slotted bar, a plurality of 75 valve-engaging elements adapted to eccentrically engage the valves, said valves being fixed to the bar in such a manner as to necessarily partake of circular movements of the bar, means longitudinally adjustable in the 80 slotted portion through which the valve-engaging elements are vertically adjusted, a common means for holding the valve-engaging elements and said first-mentioned means in relatively adjusted position with respect 85 to each other and to the bar, and manipulating means on said bar for facilitating rotatory movement of the bar whereby to simultaneously grind the valves.

JOHN J. KILBRIDE.
